(57) **CLAIM**

The ornamental design for an electric mobility jet aircraft, as shown and described.

DESCRIPTION

FIG. 1 is a perspective frontside view of the electric mobility jet aircraft, showing my new design;

FIG. 2 is a front view thereof;

FIG. 3 is a leftside view thereof;

FIG. 4 is a rightside view thereof;

FIG. 5 is a top view thereof;

FIG. 6 is a bottom view thereof;

FIG. 7 is a perspective rearside view thereof; and,

FIG. 8 is a rear view thereof.

The broken lines in the drawings illustrate portions of the electric mobility jet aircraft that form no part of the claimed design.

1 Claim, 8 Drawing Sheets
